CLAIM

The ornamental design for a dual-angle mirror, as shown and described.

DESCRIPTION

FIG. 1 is a front elevational view of a dual-angle mirror showing my new design;
FIG. 2 is a rear elevational view thereof;
FIG. 3 is a side view, taken from the left side of FIG. 1;
FIG. 4 is a side view, taken from the right side of FIG. 1;
FIG. 5 is a top plan view, the bottom plan view being a mirror image thereof; and,
FIG. 6 is a perspective view of a dual-angle mirror mounted for use.

The broken line showing a vehicle exterior rear-view mirror mount in FIG. 6 is for illustrative purposes only and forms no part of the claimed design.
